Setters Patent

3/26/1835

The Schedule referred to in these Setters Patent and making part of the same containing a description in the words of the said Luther Crane himself of his improvement in manufacturing Cotton into Yarn.

Be it known that I Luther Crane have invented, constructed, made and applied to use, a new and useful improvement in the Mode of Making or manufacturing Cotton into Yarn.

The invention or improvement consists in the addition of a tube to a part of the machine now in use for the spinning, or making, Cotton Yarn. A model of that part of the machine to which this improvement is attached accompanies the petition. Without the improvement this part of the machine consists of a Spindle or Wheel and fiber; the spindle is fastened to a transverse rail at one end and passes through the wheel the wheel turns upon the spindle. It is necessary that the spindle should pass up and down through the wheel by the motion of the transverse rail to which it is attached.

The wheel turns on the spindle and gives to the spindle a tremulous motion which injures the operation of the machine. To prevent this motion and to enable the machine to be operated with more rapidity, this tube is introduced into the machine. The tube is firmly attached to one end of the spindle passes up and down through the tube and the wheel turns upon the tube without affecting the spindle the tube being firmly fixed and receiving the motion of the wheel the tremulous motion of the spindle is prevented by the introduction of the tube. I declare that the above is a true specification of my said improvement as above described. I have hereunto set my hand and seal this Eighteenth day of February in the Year of our Lord

one thousand eight hundred and thirty five
